UNITED STATES PATENT OFFICE.

JULIUS DORNETH, OF BERLIN, GERMANY, ASSIGNOR TO TYPOGRAPH G. M. B. H., OF BERLIN, GERMANY.

LINE SETTING AND CASTING MACHINE.

1,115,516.

Specification of Letters Patent.

Patented Nov. 3, 1914.

Application filed January 15, 1913. Serial No. 742,298.

To all whom it may concern:

Be it known that I, JULIUS DORNETH, a subject of the German Emperor, and residing at Berlin, Germany, have invented certain new and useful Improvements in Line Setting and Casting Machines, of which the following is a specification.

My invention relates to improvements in line-setting and casting machines, and more particularly in line-setting and casting machines of the class described for example in the patents of the United States Nos. 1,000,157, 1,017,929, and 1,021,828. In machines of this type matrix bars containing the various characters are suspended on inclined wires which are mounted on a rocking frame and converge toward their lower ends, where they are arranged in vertical parallel tiers, so that when rocking the said frame into assembling position the matrices slide downward along their wires and are assembled to form a line from which the line of type can be cast. In machines of this class it has been suggested to arrange the wires with their assembling ends not in the ordinary way along two vertical lines of tiers, but along four tiers, in which case the matrices suspended from the outer tiers are provided with bent head portions, so that they pass between the inner tiers of wires. Thereby the outer matrix bars are suspended from their wires in inclined positions. Furthermore, in order to permit the matrix bars to be shifted vertically upward and downward, the wires of the outer tiers must be disposed at different levels from those of the inner tiers. This however is objectionable, because the matrix bars of the inner and outer tiers must be made with different lengths.

The object of the improvements is to so construct the matrix bars, that all the wires which horizontally correspond to each other in the four tiers are disposed at the same level, and that the lengths of corresponding matrix bars are the same.

With this and other objects in view my invention consists in providing the matrix bars with double bends at such parts of their lengths, that in assembling the matrix bars the said bends are located below all the wires, so that the parts of the bars which carry the types are disposed on the median plane of the inner tiers.

In order that my invention be more clearly understood an example embodying the same has been shown in the accompanying drawing.

Figure 1 illustrates a matrix frame, and Fig. 2 shows a partial vertical cross-section of the wire carrying frame taken through the assembling end of the wires and two matrix bars suspended therefrom.

Referring to the example illustrated in the drawing, the wires *c* and *c'* are disposed at their assembling ends in four vertical tiers. In the preferred form shown in the drawing the corresponding wires of the outer and inner tiers are disposed at the same levels, though it is not absolutely necessary to dispose the same in this way. Those of the matrix bars *a* which are suspended from the outer wires *c'* are formed with double bends *e* and these double bends are located at such parts of the lengths of the matrix bars, that in the assembled position they are below all the wires *c*, *c'*. Thereby the lower portions *a*² of the matrix bars which carry the types are disposed in the median plane passing between the inner wires *c*. In the known construction the double bends of the matrix bars are located near the top and they pass between the wires of the inner tiers, and the bars are located with their upper parts between the inner tiers of wires *c*, *c'*. By providing the double bends at points below the wires I am enabled to dispose the upper parts of the matrix bars in such a way that it is not necessary to pass the same between the wires of the inner tiers. They extend downward directly at the sides of their tiers, and in the example shown in the drawing they are located at the inner sides of their tiers, that is between their tiers and the adjacent one of the inner tiers. By thus disposing the double bends below the wires, I am able to arrange the assembling ends of the wires *c* or *c'* at smaller distances vertically from one another, because it is not necessary to pass the matrix bars between the same, and the play of the eyes *f* provided at the upper ends of the matrix bars is sufficient to permit the upward shifting movement of the matrix bars. By reason of the location of the double bends at a considerable distance below the point of suspension the matrix bars are inclined at a smaller angle to the

vertical than in such cases where the said double bends are near the upper ends of the bars.

At their upper ends the matrix bars are provided with the usual eyes whereby they are suspended from the wires. As shown these eyes are pivotally connected to the matrix bars, so that they can be set in two positions for raising or lowering the bars, 16 as is known in the art.

When sliding downward on the guiding wires *c* or *c'* into assembling position the matrix bars fall on the matrix bars which have previously been assembled and are in 15 inclined position. Therefore it happens that the downwardly moving matrix bars strike with their lower ends on the assembled bars and injure the type on the face of the bars. To avoid this the matrix bars 20 are notched out at their lower ends as at *b* a length exceeding the height of the line of type.

I claim:

1. In a line setting and casting machine, 25 the combination with wires extending from distributing to assembling position and arranged at their assembling ends in four parallel vertical tiers, of matrix bars adapted to slide on said wires without leaving the same, the matrix bars of the outer tiers having double bends at points below the tiers of wires and located with their matrix carrying ends substantially in the median plane of the inner tiers.

35 2. In a line setting and casting machine, the combination with wires extending from distributing to assembling position and arranged at their assembling ends in four parallel vertical tiers, of matrix bars adapted to slide on said wires without leaving the same, the matrix bars of the outer tiers having double bends at points below the tiers of wires and located with their matrix carrying ends substantially in the median plane 40 of the inner tiers and with their upper ends between the tier of wires carrying the same and the adjacent inner tier.

3. In a line setting and casting machine, 50 the combination with wires extending from distributing to assembling position and arranged at their assembling ends in four parallel vertical tiers, of matrix bars adapted to slide on said wires without leaving the same and having hinged eyes for suspension on said wires, the matrix bars of the outer tiers having double bends at points below the tiers of wires and located with their matrix carrying ends substantially in the median plane 55 of the inner tiers.

60 4. In a line setting and casting machine, the combination with wires extending from distributing to assembling position and arranged at their assembling ends in vertical tiers, of matrix bars adapted to slide on said 65 wires without leaving the same and having

notches at their lower ends equal in length at least to the height of the matrices on the type bars.

5. In a line setting and casting machine, 70 the combination with wires extending from distributing to assembling position and arranged at their assembling ends in four parallel vertical tiers, of matrix bars adapted to slide on said wires without leaving the same and having notches at their lower ends equal 75 in length at least to the height of the matrices on the matrix bars.

6. In a line setting and casting machine, 80 the combination with wires extending from distributing to assembling position and arranged at their assembling ends in four parallel vertical tiers, of matrix bars adapted to slide on said wires without leaving the same and having notches at their lower ends equal 85 in length at least to the height of the matrices of the matrix bars, the matrix bars of the outer tiers having double bends at points below the tiers of wires and located with their matrix carrying ends substantially in the median plane of the inner tiers.

7. In a line setting and casting machine, 90 the combination with wires extending from distributing to assembling position and arranged at their assembling ends in two inner and at least one outer parallel vertical tiers, 95 of matrix bars adapted to slide on said wires without leaving the same, the matrix bars of the outer tier having double bends at points below the tiers of wires and located with their matrix carrying ends substantially in the median plane of the inner tiers.

8. In a line setting and casting machine, 100 the combination with wires extending from distributing to assembling position and arranged at their assembling ends in two inner and at least one outer parallel vertical tiers, 105 of matrix bars adapted to slide on said wires without leaving the same, the matrix bars of the outer tier having double bends at points below the tiers of wires and located with their matrix carrying ends substantially in the median plane of the inner tiers and with 110 their upper ends between the tier of wires carrying the same and the adjacent inner tier.

9. In a line setting and casting machine, 115 the combination with wires extending from distributing to assembling position and arranged at their assembling ends in two inner and at least one outer parallel vertical tiers, 120 of matrix bars adapted to slide on said wires without leaving the same and having hinged eyes for suspension on said wires, the matrix bars of the outer tier having double bends at points below the tiers of wires and located with their matrix carrying ends substantially in the median plane 125 of the inner tiers.

10. In a line setting and casting machine, 130 the combination with guiding members ex-

tending from distributing to assembling position and arranged at their assembling ends in at least three parallel vertical tiers, of matrix bars adapted to slide on said guiding members without leaving the same, the matrix bars of at least one of said tiers having double bends at points below the tiers of wires.

11. In a line setting and casting machine, the combination with wires extending from distributing to assembling position and arranged at their assembling ends in vertical

tiers, of matrix bars adapted to slide on said wires without leaving the same and having notches at their lower ends equal in length 15 at least to the height of the matrices on the matrix bars.

In testimony whereof I hereunto affix my signature in the presence of two witnesses.

JULIUS DORNETH.
